UNITED STATES PATENT OFFICE.

EDWARD CLIFF, OF NEWARK, NEW JERSEY.

DESIGN FOR A HOSE-NOZZLE.

SPECIFICATION forming part of Design No. 30,956, dated June 6, 1899.

Application filed May 9, 1899. Serial No. 716,171. Term of patent 7 years.

To all whom it may concern:

Be it known that I, EDWARD CLIFF, a citizen of the United States, residing at Newark, in the county of Essex and State of New Jersey, have invented and produced a new and original Design for a Hose-Nozzle, of which the following is a specification, reference being had to the accompanying drawing, forming part thereof, and representing, in a perspective view, a hose-nozzle bearing and incorporating my design.

The leading feature of my design consists of the form and configuration of the hose-nozzle, substantially as shown in the drawing.

15 In the drawing, A designates the cylindrical body of the hose-nozzle, having at its base

end the annular enlarged cylindrical portions B C and at its discharge end the cylindrical cap D, the latter bearing the annular beading E and having the rounded upper edges F ²⁰ leading to the contracted tubular discharge portion G, substantially as shown.

What I claim is—

The design for a hose-nozzle, substantially as shown and described. ²⁵

Signed at New York, in the county and State of New York, this 8th day of May, A. D. 1899.

EDWARD CLIFF.
